UNITED STATES PATENT OFFICE.

ADOLPH GUENTHART, OF WILMAR, CALIFORNIA.

METHOD OF FORMING OUTSIDE DOUBLE PICKS ON ROUND SEAMS.

Application filed January 5, 1926. Serial No. 79,496.

My invention relates to the method of forming outside double picks on round seams and to the dies used for making such picks.

5 An object of my invention is to make an outside double pick on round seams as utilized in oil well operations. The previous practice has been to rivet the seams of built up casing sections which are placed in the 10 well to prevent collapse of the wall, the well boring tools, pumps and other appliances extending downwardly through the casing. It is necessary to have the casing smooth on the inside surface on account of the various tools used therein as these would 15 readily knock off the rivets if they projected inwardly, therefore in the riveted type of round seams the custom has been to use flat headed rivets securing an inner tube section to an outer tube section. As 20 these tube sections are made of thin metal the rivets frequently shear and hence the casing section is useless.

It is the common practice to build up a 25 casing length, say up to 20 feet in length, by utilizing short tubular sections of sheet metal riveted together at the seams with counter-sunk rivets on the inside surface, these tubes sections telescoping one on the 30 other inwardly and outwardly continuously until the full length of the tube is made up. The individual tube sections are rarely over three feet in length and as 35 the tube sections are staggered to break joint, an overlapping of about a foot and a half is given at each end.

To hold these round seams together, they have in the past been riveted as above described, with the counter-sunk rivets on the 40 inside and also in some cases by utilizing a single pick from the inside surface. A pick as defined to well boring means a bulge or the like formed in sheet metal; thus forming an indentation on one side of the metal 45 and a slight projection on the other side and causing two round rings or tubes of metal to hold together.

50 My outside double pick for round seams comprises bulging two concentric rings of metal fitting one tight on the other outwardly from the inside surface and at the same time depressing the apex of what would be a single pick inwardly. The apex is only depressed inwardly a sufficient extent so that 55 it does not extend inwardly beyond the in-

side surface of the ring. Therefore examined from the inside my outside double pick has an annular depression on the inside and an annular pressed out part on the outside. When successive rings are built up 60 with this type of pick, it is practically impossible to pull them apart as there are no rivets to shear and the double bending of the metal forms an interlocking fit.

Moreover, with this type of jointing there 65 is no danger of individual sections comprising a single inside tube and an outer tube thereon telescoping further than intended as the interlocking double pick prevents longitudinal movement.

70 My method consists in the manner of forming the above mentioned type of joint and the dies forming my invention and in the die acting on the inside having an annular rim with a central depression cooperating 75 with an outside die having a peripheral edge, an annular recess and a central projection.

75 My invention will be more readily understood from the following description and drawings, in which;

Fig. 1 represents a well casing section built up of a series of rings fitting one into the other and secured by my form of outside double pick securing each of the tube sections to the next adjacent.

80 Fig. 2 is an enlarged section of Fig. 1, showing the manner of making up the casing and a suitable arrangement of double picks.

85 Fig. 3 is a section through Fig. 2, on the line 3—3, illustrating some of the picks in vertical section.

90 Fig. 4 is a horizontal section on the line 4—4 of Fig. 2, on an enlarged scale, indicating a suitable type of longitudinal joint.

95 Fig. 5 is a detail perspective view of a double pick as viewed from the outside.

100 Fig. 6 is a detail perspective view of a double pick as viewed from the inside.

105 Fig. 7 is a section through dies and sheet metal rings in the formation of my outside double pick.

110 Fig. 8 is a section showing in partial perspective a double pick.

Referring particularly to Figs. 1 to 4, a casing section suitable for work in oil wells is indicated by the numeral 1. This is built up of a plurality of telescopically fitting tubes and of a short section as shown par-

ticularly in Fig. 3. An inner tube 2 fits telescopically inside of an outer tube 3, these being secured together by a double pick 4. The tubes are made with a longitudinal seam 5 which for the inside tubes have rivets 6 with counter-sunk heads on both ends. These are preferably lap joint seams. The outer tube sections 3 have a longitudinal lap 7 secured together by rivets 8 with counter-sunk heads on the inside and rounded heads on the outside. With a series of double picks 4 around the periphery of these telescoping tube sections they are held rigidly together so that they cannot be further telescoped together or pulled apart in any ordinary usage.

These tube sections 2 and 3 may be of any suitable length and are rarely over three feet in length each. Thus the overlapping of the sections is rarely of a foot and a half. However, such distances may be departed from and my pick may be utilized in connecting long cylinders or the like together, end to end. Moreover, with my type of pick it is not necessary that the ends of the individual tube sections abut together. However, as illustrated, in conformity with the usual practice, the inner series of the sections have abutting end joints 9 and the outer tube sections have abutting joints 10.

In the manner of forming my double pick I utilize dies as illustrated particularly in Fig. 7, in which the inner die 11, preferably formed cylindrical, has an annular projection 12 sloping outwardly from the peripheral edge 13, then having a downward curve as indicated by the numeral 14 with a reverse bottom curve indicated by the numeral 15. Instead of these various portions of the die being curved as above described they can be made angular if the material to be operated upon can be given sharp bends.

The outside die 16 has an annular recess 17 having an inward curve 18 from the peripheral edge 19, an outward curve 20 and a projection 21 in the center having a reverse curve. These curved surfaces may be formed angular if desired or of any other suitable shape so that the inner and outer dies will conform and cooperate together.

In Fig. 7, an inside tube 2 is indicated as the lower and the outside tube 3 as the upper sheet of metal. When the dies are forced together it will therefore be seen that the metal is forced outwardly forming an annular depression 22 as indicated in Figs. 6 and 8; this forming an annular projection or bottom 23 on the outside as indicated in Figs. 5 and 8. The projection 21 holds the metal inwardly forming a central socket 24 on the outside as indicated in Figs. 5 and 8; this forming a central circular surface 25 on the inside as indicated in Figs. 6 and 8.

The dies are so shaped and the operation performed in such a manner so that the cir-

cular surface 25 would be on the same radius as the inner surface 26 of the tube section. It would not extend inwardly of such surface and preferably should be as close as possible to such surface in order to have as sharp bends as possible in the double pick.

It will thus be seen that the round or circular seams in tubular or cylindrical sections are held together from relative longitudinal movement by these double curves formed in the sheet metal; that is, the annular depression 22 from the inside forcing the sheet metal outwardly forming the annular projection 23 and the inwardly formed central socket 24 causes the binding of two sheets of metal together. This forms an equivalent of riveted joints at the seams without any perforating of the metal as is required for riveting or without any rivets being inserted through the sheet metal.

It will be obvious that the double-pick type of joint for round seams differentiates from other constructions which rely on rolls which are adapted to force annular portions of the double sections outwardly or inwardly in that the dies which are employed merely force small restricted circular areas of the metal outwardly or inwardly.

It will be obvious that a double pick type of joint for round seams may be utilized with other types of cylindrical tubes and for many different purposes other than that above described. The specific shape of double picks and the specific shape of dies may also be changed from those illustrated to suit different circumstances. The type of double pick joint however, so formed and the method of making would be within the spirit of my invention as set forth in the description, drawings and claims.

Having described my invention, what I claim is:

1. The method of making outside double picks on round seams, comprising positioning tubular sections concentrically and in close contact, forcing the metal of both sections outwardly forming an annular depression on the inside and an annular projection on the outside, at the same time forcing a portion of the metal in the center of the annuluses inwardly, forming a centrally positioned socket on the outside and a centrally positioned substantially circular surface on the inside.

2. The method of making outside double picks as claimed in claim 1, in which the inward pressing to form the socket is insufficient to thrust the circular surface on the inside inwardly beyond the surface of the adjacent underformed material.

3. The method of fastening together telescoped tube sections, consisting of pressing outwardly circular areas of the sections and pressing inwardly portions of said areas, thus forming buttons on the inside of the in-

ner section, the bottoms of which are completely exposed to the inside of the inner section.

4. The method of fastening together telescoped tube sections, which consists of applying a die to the inside of the inner section, which die has an annular projection thereon, forcing the metal of both sections outwardly thereby, and simultaneously applying a die to the outside of the outer section opposite the recess within the annular projection on the inner die to hold the metal of the sections within the annular projection from being forced outwardly by the inner die.

5. The method of making outside double picks on round seams, comprising positioning tubular sections concentric one to the other and in close engagement, forcing metal outwardly in a small annular ring, and at the same time holding the central portion inwardly.

6. The method of fastening together telescoped tube sections, which consists of forming projections upon the outer section by pressing portions of the inner section outwardly, and pressing the centers of the portions inwardly in such a manner as to form restricted circular recesses on a small inside area of the inner section, the bottoms of which are completely exposed to the inside of the inner section.

7. The method of fastening together telescoped tube sections, which consists of applying an inwardly directed pressure to small circular areas on the outside of the outer section, and simultaneously applying pressure to portions of the inside of the inner section about the mentioned areas, and thus deforming the metal of both sections.

8. The method of fastening together telescoped tube sections, which consists of applying a die to the inside of the inner sec-

tion, which die has a small annular projection thereon, and forcing the metal of both sections outwardly, thereby and at the same time holding a portion of the metal being forced outwardly, inwardly against the action of said die.

9. The method of fastening together telescoped tube sections, which consists of forming projections upon the outer section by pressing spots on the inner section outwardly, and holding the centers of the spots inwardly in such a manner as to form recesses around said spots on the inside of the inner section, the bottoms of which are completely exposed to the inside of the inner section.

10. The method of fastening together telescoped tube sections, which consists of pressing outwardly spots on the sections, and holding inwardly portions of said spots, thus forming projections on the inside of the inner section, the bottoms of which are completely exposed to the inside of the inner section.

11. The method of fastening together telescoped tube sections, which consists of applying an inwardly directed pressure to spots on the outside of the outer section, and simultaneously applying pressure to portions of the inside of the inner section about the mentioned spots, and thus deforming the metal of both sections.

12. The method of fastening together telescoped tube sections, which comprises pressing outwardly spots on the surfaces of the sections, and holding inwardly portions of said spots thus forming projections on the inside of the inner section, the bottoms of which are completely exposed to the inside of the inner section.

In testimony whereof I have signed my name to this specification.

ADOLPH GUENTHART.
